ENNO BECKER, OF BREMEN, GERMANY

SHEET PILING FOR HEAVY LOADS

Application filed November 20, 1930, Serial No. 497,047, and in Germany June 14, 1928.

In the construction of sheet piling undergoing heavy loads it is known to connect I-sections arranged at distances apart and with their webs vertical to the middle plane of the sheet piling with flat plates, by disposing each I-section between two such flat plates arranged parallel in the said plane. In connecting two "ramming units" comprising one I-iron and two plates at the two ends of the flat plates, however, difficulties are encountered in bringing pile elements into inter-engagement for the purpose of ramming, owing to the differences in distance between two locking members situated on one side of the webs of the I-sections, which arise on account of unavoidable inaccuracies of the single parts to be connected, which inaccuracies may be summarized in a structure of some greater length.

It is also known to provide the ends of the flanges of I-sections with locking members and to connect them by means of flat plates provided with corresponding locking members. With this construction also, difficulties arise in ramming, from the employment of the flat plates, which are not sufficiently rigid and the ramming of which is difficult, or in the case of considerable lengths even impossible.

These defects are obviated, according to the present invention, by a new combination between the I-sections and flat plates, in which the plates are disposed on one side (the outside) of the wall only.

The I-sections applied according to the invention are of the ordinary general form, but have unequal flanges with that at one end somewhat wider and thicker and so of greater strength than that at the other. The weaker flange of each section is designed to be slid or inserted into a plate and rigidly connected thereto by welding, in known manner, while the wider and thicker flange at the other end of the web forms an anchorage and counterbalance for the greater mass on the plate side, and brings the axis of flexion as near as possible to the so-called "wall axis" or middle plane of the wall.

I-section walls, such as here contemplated, present a perfectly staunch smooth front sur-

face. This is a condition which is desirable for shipping, but is attended with the drawback that structural members which are indispensable in the case of such walls, can be attached only in such a manner as to project. In order to remedy this drawback, the invention provides for the insertion, according to requirements, of channel sections between the plate irons in which channel irons, mooring rings, ladders etc: can be accommodated.

In ramming a wall of sheet piling, the piling members of irons gradually tend to assume a slanting position, in that the upper end diverges towards the unrammed side of the wall. It is, therefore, necessary, now and again, when the tilt has become excessive, to compensate or return the joints to vertical position. This is difficult to accomplish in the case of closed I-section walls because, unlike wooden piling members, the irons cannot be cut in the form of wedges. The insertion of the channel members enables the free locking edge to be forced nearer to the finished wall, at the upper end, and to draw it further apart at the lower end, so that the free "locking" edge will assume the vertical position, as the inserted channel iron may comparatively easily be brought to a wedge shape of the required angle. In this manner, the insertion of the channel section enables balanced ramming to be obtained, or in other words to return the free edge of the piling to coincide with a vertical line.

The drawings show the sheet-piling wall in cross section in two constructional forms, Fig. 1 illustrating one form and Fig. 2 illustrating another.

In Fig. 1 a is an I-section, having a thickened flange b at one end disposed at the side facing the solid ground, while the opposite flange c facing the trench or water side in case of a quay wall is slipped in dove-tail and groove fashion into a flat plate d provided with lugs or projections e which tightly embrace said flange.

Compound units comprising an I-iron a and a plate d rigidly attached thereto as by welding are driven one after the other and connected with each other in known manner,

so as to provide a perfectly flat surface on the outer side of the wall.

In Fig. 2 a channel section *f* is shown inserted in the wall for the purpose of balancing the ramming and at the same time, as already described, to accommodate structural members (not shown) such as mooring rings, ladders and the like.

Having now particularly described and ascertained the nature of my said invention and in what manner the same is to be performed, I declare that what I claim is:

1. A piling wall construction comprising flat iron-plate sections joined together by interlocking marginal end connection one to another and I-shaped iron-beam members backing the same in right-angular or T relation; said members having their flanges at one end dove-tailed in and welded to the plate sections and heavier flanges at the other end providing firm anchorage and counterbalance for the structure as also bringing the axis of flexion nearly as possible to the middle plane thereof.

2. A piling wall construction comprising flat plate sections connected by interlocking marginal end fit with one another and I-shaped beam-members dove-tailed to and rigidly united with the mid-portions of said section in T or right-angular relation; said members being unconnected at their opposite ends and thereat formed with enlarged flanges effecting firmer grip into the soil for counterbalancing purposes and bringing the axis of flexion nearly as possible to the middle plane of the wall structure.

3. A piling wall construction comprising flat plate sections joined together end to end by interlocking connection with one another and I-shaped backing members connected to the mid-portions thereof in T or right-angular relation with laterally extended free ends formed wider and thicker than at the others for as nearly as possible centralizing the mass and bringing the axis of flexion toward the middle plane of the wall structure, combined with U-shaped sections applied at intervals between the flat plate sections for correcting or compensating inclination and providing for structural appliances such as ladders within the face of the wall.

4. In a piling wall construction, a structural unit comprising a flat plate-section and an I-shaped beam-like member rigidly united thereto in T or right-angular relation by dove-tailed connection and welding together for driving or ramming as a unit; the free end of said beam-like member being formed with an enlarged flange or head for firm anchorage and counterbalance as also to throw the axis of flexion nearly as possible toward the center plane of the unit.

5. A piling wall construction comprising flat plate-sections having interlocking marginal end connection together along the line

of the wall, and I-shaped members having dove-tail and rigid connection with the mid-portions of said sections in right-angular relation thereto along their lengths; said members being formed with the flange or head at the end unconnected with the sections wider and thicker than at the other for nearly as possible centralizing the mass and bringing the axis of flexion toward the middle plane of the wall structure.

6. A piling wall construction comprising ramable units of flat plate and I-shaped members connected in right-angular or T relation by dove-tailing and welding together, the plate-portions being connected marginal end to end by interlocking-joint fit with one another and the I-members being free at one end; together with U-shaped members connected at intervals between the aforesaid plate-sections for correcting or compensating for inclination as also providing for appliance of structural parts within the surface of the wall.

7. A piling wall construction comprising flat plate-sections having interlocking marginal end connection with one another along the length of the wall, and I-shaped members having dove-tail and rigid connection with the mid-portions of said sections at right-angular or T relation thereto along their length; said I-shaped members being formed with the flanges at their free ends wider and thicker than at the other for nearly as possible centralizing the mass and bringing the axis of flexion toward the middle plane of the wall structure and each I-shaped member and plate-section with which it connects together providing a ramable unit of the structure.

8. A piling wall construction comprising ramable units of flat plate and I-shaped members connected in right-angular or T relation by dove-tailing and welding together, the plate-portions being connected marginal end to end by interlocking-joint fit with one another and the I-members being free at one end and formed with wider and thicker flanges thereat than on the other so as nearly as possible to centralize the mass and bring the axis of flexion of the structure toward the middle plane.

9. A piling wall construction composed of units of flat plate and I-beam members rammed into place together; said plates being connected together by interlocking marginal end engagement with one another in formation of a smooth wall surface and said I-beams being connected as backings at lateral or T relation thereto by dove-tail fit and rigid connection of end flanges with the mid-portions thereof, the flanges at the opposite free ends of the beams being made wider and thicker for strengthening and bringing the center of mass as also the flexion axis of the

wall structure nearly as possible to the middle-plane thereof.

10. A piling wall construction composed of units of flat plate-sections and I-beam members connected in **T** or right-angular relation by dove-tailing and welding together along the mid-line portions of the plates; the plate-sections being joined one to another by interlocking marginal-end engagement in formation of a smooth wall surface and said I-beam members being free at their opposite ends with the flanges thereat formed wider and thicker than at the others for strengthening and bringing the mass center as also the flexion axis of the wall structure nearly as possible to the middle-plane thereof.

11. A piling wall construction composed of units of flat plate-sections and I-beam members connected in **T** or right-angular relation by dove-tailing and welding together along the mid-line portions of the plates; the plate-sections being joined one to another by interlocking marginal-end engagement in formation of a smooth wall surface and said I-beam members being free at their opposite ends with the flanges thereat formed wider and thicker than at the others for strengthening and bringing the mass center as also the flexion axis of the wall structure nearly as possible to the middle-plane thereof, combined with **U**-shaped plate sections connected at intervals between the plate sections of the units for counteracting inclinations and providing recess spaces for accommodation of ladders or other appliances.

In testimony whereof I affix my signature.
ENNO BECKER.
